United States Patent Office.

E. D. RICHARDSON, OF CHARDON, OHIO.

Letters Patent No. 92,362, dated July 6, 1869.

IMPROVEMENT IN YARD-MARK AND KNIFE.

The Schedule referred to in these Letters Patent and making part of the same.

To all whom it may concern.

Be it known that I, E. D. RICHARDSON, of Chardon, in the county of Geauga, and State of Ohio, have invented a new and improved Combined Yard-Mark and Knife; and I do hereby declare that the following is a full, clear, and exact description thereof, which will enable others skilled in the art to make and use the same, reference being had to the accompanying drawings, forming part of this specification, in which—

Figure 1 represents a plan or top view of my improved yard-mark and knife.

Figure 2 is a side view of the same.

Similar letters of reference indicate corresponding parts.

This invention relates to a new device to be applied to counters, in stores and salesrooms, and has for its object to serve at once as a measure, like the ordinary buttons put into counters, and as a knife for cutting the edge of the cloth or fabric measured, preparatory to tearing the same, and for cutting twine, &c.

The invention consists in the application of a blade, A, which is sunk into a recess formed at the back edge of the counter, and which has a top plate or button, a, that rests on the counter.

The blade has a hook, b, formed on it, which fits under a pin, c, that is arranged in the recess of the counter.

When the device is simply suspended from the knob a, it serves as a part of a yard or other measure, while it will, when elevated, carry its inclined cutting-edge d above the counter, as shown by red lines in fig. 2; and will, when pressed down, make an incision in any fabric, twine, or other article placed under it.

The hook prevents it from being readily drawn out, and lost by careless persons, and still permits its removal when desired.

The recess in the counter may be lined by a metallic box, B, as shown.

The fabric or other material may also be cut by forcing it under the button into the fork of the knife, so that it will be brought in contact with the cutting-edge.

Having thus described my invention,
I claim as new, and desire to secure by Letters Patent—

As an improved article of manufacture, a combined yard-mark and cutter, made and operating substantially as herein shown and described.

E. D. RICHARDSON.
